A. W. MURRAY

ICE CREAM CONE OR LIKE ARTICLE

Filed Jan. 20, 1928

Fig. 1.

Fig. 2.

Inventor:
Alexander W. Murray

UNITED STATES PATENT OFFICE.

ALEXANDER W. MURRAY, OF WELLESLEY FARMS, MASSACHUSETTS.

DESIGN FOR AN ICE-CREAM CONE OR LIKE ARTICLE.

Application filed January 20, 1928. Serial No. 24,947. Term of patent 14 years.

To all whom it may concern:

Be it known that I, ALEXANDER W. MURRAY, a citizen of the United States, residing at 4 Pine Ridge Road, Wellesley Farms, in the county of Norfolk and State of Massachusetts, have invented a new, original, and ornamental Design for an Ice-Cream Cone or like Article, of which the following is a specification, reference being had to the accompanying drawing, forming part thereof.

Figure 1 is a plan view of top and Figure 2 is a vertical view in elevation, of an ice cream cone, showing my new design.

I claim:

The ornamental design for an ice cream cone or like article, as shown.

Dated: January 19, 1928.

ALEXANDER W. MURRAY.
